Primary Examiner — T. Chase Nelson*Assistant Examiner* — Michelle E Wilson(74) *Attorney, Agent, or Firm* — Dowell & Dowell, PC(57) **CLAIM**

The ornamental design for a structural member, as shown and described.

DESCRIPTION

FIG. 1 is a front right perspective view of a structural member showing my new design;

FIG. 2 is a front left perspective view thereof;

FIG. 3 is a rear left perspective view thereof;

FIG. 4 is a rear right perspective view thereof;

FIG. 5 is a top plan view thereof;

FIG. 6 is a bottom plan view thereof;

FIG. 7 is a left side view thereof;

FIG. 8 is a right side view thereof;

FIG. 9 is a front elevation view thereof;

FIG. 10 is a rear elevation view thereof; and,

FIG. 11 is a cross sectional view thereof taken along line 11-11 of FIG. 6.

The structural member is shown broken away to indicate that any portion of the article beyond what is shown forms no part of the claimed design.
